(57) **ABSTRACT**

An extrusion system including a press with a chassis, a slider mounted to be mobile vertically on the chassis and an actuating arrangement that moves the slider, a hollow container receiving a billet and having at one end an extrusion die and at the other end a piston mobile in translation horizontally in the container, and a movement transformation system arranged between the slider and the piston to transform the vertical movement in translation of the slider into horizontal movement in translation of the piston. With an arrangement of this kind, it is possible to use a press of higher power.

**EXTRUSION SYSTEM INCLUDING A PRESS
AND AN EXTRUSION DIE WITH TWO
MUTUALLY-PERPENDICULAR DIRECTIONS
OF MOVEMENT**

**CROSS-REFERENCES TO RELATED
APPLICATIONS**

This application claims the benefit of the French patent application No. 2200736 filed on Jan. 28, 2022, the entire disclosures of which are incorporated herein by way of reference.

FIELD OF THE INVENTION

The present invention relates to the general field of extrusion systems, in particular for the extrusion of metal, for example aluminum, billets. It concerns, in particular, an extrusion system including a press, in particular a forging press, and an extrusion die that has two mutually-perpendicular directions of movement.

BACKGROUND OF THE INVENTION

FIG. 6 shows a prior art extrusion system 600. The extrusion system 600 includes a container 602 that is hollow and enables reception of a billet 604, for example an aluminum billet. At one of the ends of the container 602 is disposed an extrusion die 606 that has a passage 608 through which the extruded profile 610 passes.

At the other end of the container 602 a piston 612 is mounted to be mobile in translation in the container 602. The piston 612 is moved by a horizontal displacement press that is outside the container 602 and has a piston rod 614 secured to the piston 612.

The operation of an extrusion system 600 of this kind is then as follows. A heated billet 604 is introduced into the container 602 between the piston 612 and the extrusion die 606. The press moves the piston 612 toward the extrusion die 606, which pushes the billet 604 through the extrusion die 606 to form the extruded profile 610.

Although an arrangement of this kind offers high performance, the presses employed have limited power and it is therefore necessary to find an arrangement that enables higher powers to be obtained.

SUMMARY OF THE INVENTION

An object of the present invention is to propose an extrusion system that has a high thrust power, in particular due to the use of a vertical axis press and a horizontal axis die.

To this end there is proposed an extrusion system including:

a press with a chassis, a slider that is mounted to be mobile vertically on the chassis and actuating means that move the slider alternately downward and upward, at least one container that is hollow to receive a billet and has at one of its ends an extrusion die and at the other of its ends a piston mounted to be mobile in translation horizontally in the container, and for each piston a movement transformation system that is arranged between the slider and the piston to transform the vertical movement in translation of the slider into horizontal movement in translation of the piston.

With an arrangement of this kind, it is possible to use a press of higher power.

2

In accordance with one particular embodiment, each movement transformation system includes a pinion the rotation axis of which is horizontal and perpendicular to the direction of movement in translation of the piston, a first rack that meshes with the pinion and is secured to the slider, and a second rack that meshes with the pinion and is secured to said piston.

There is advantageously only one piston, and the second rack advantageously meshes with a lower part of the pinion.

There are advantageously two pistons and each second rack advantageously meshes with a lower part of the pinion.

There are advantageously two pistons and one of the second racks advantageously meshes with a lower part of the pinion and the other of the second racks advantageously meshes with an upper part of the pinion.

In accordance with one particular embodiment, each movement transformation system includes an arm that has a first end mounted in articulated manner on the slider and a second end mounted in articulated manner on the piston.

BRIEF DESCRIPTION OF THE DRAWINGS

The features of the invention mentioned hereinabove and others will become more clearly apparent on reading the following description of one embodiment, said description being given with reference to the appended drawings, in which:

FIG. 1 is a diagrammatic representation of an extrusion system in accordance with a first embodiment of the invention,

FIG. 2 is a view in the direction of the arrow F in FIG. 1 for a first variant of the first embodiment of the invention,

FIG. 3 is a view in the direction of the arrow F in FIG. 1 for a second variant of the first embodiment of the invention,

FIG. 4 is a view in the direction of the arrow F in FIG. 1 for a third variant of the first embodiment of the invention,

FIG. 5 is a diagrammatic representation of an extrusion system according to a second embodiment of the invention, and

FIG. 6 already described, is a diagrammatic representation of a prior art extrusion system.

**DETAILED DESCRIPTION OF THE
PREFERRED EMBODIMENTS**

FIG. 1 shows an extrusion system 100 according to a first embodiment of the invention and FIG. 5 shows an extrusion system 500 according to a second embodiment of the invention.

The extrusion system 100, 500 includes a press 102, 502 with a chassis 101, 501 and a slider 104, 504 that is mounted to be mobile vertically on the chassis 101, 501. The movement in translation of the slider 104, 504 on the chassis 101, 501 is guided by any guide means known to the person skilled in the art, such as guide rails, for example.

The press 102, 502 also includes actuating means 106, 506 that move the slider 104, 504 vertically and alternately downward and upward. The actuating means 106, 506 are for example of the mechanical type with a crank and link system or of the hydraulic type or of the screw type.

The press 102, 502 is advantageously a forging press the slider 104, 504 of which moves vertically and has a varying much higher power than the horizontal axis presses of the prior art extrusion systems.

The extrusion system 100, 500 also includes at least one container 152, 552a-b that is hollow and enables it to receive a billet 10, for example an aluminum billet. At one of the

ends of the container **152**, **552a-b** is disposed an extrusion die **154**, **554a-b** that includes a passage **156**, **556a-b** through which the extruded profile **160**, **560a-b** passes.

At the other end of the container **152**, **552a-b** a piston **162**, **562a-b** is mounted to be mobile in translation in the container **152**, **552a-b**. The piston **162**, **562a-b** is extended outside the container **152**, **552a-b** by a piston rod pinion, **564a-b**. The end at which the extrusion die **154**, **554a-b** is disposed is opposite the end at which the piston **162**, **562a-b** and the piston rod **164**, **564a-b** are disposed.

Each piston **162**, **562a-b** is mobile horizontally, that is to say, perpendicularly to the direction of movement of the slider **104**, **504**.

The extrusion system **100**, **500** also includes, for each piston **162**, **562a-b**, a movement transformation system **180**, **580a-b** that is arranged between the slider **104**, **504** and the piston **162**, **562a-b** and more particularly the piston rod **164**, **564a-b** secured to the piston **162**, **562a-b**, to transform the movement in translation of the slider **104**, **504** in the vertical direction into movement in translation of the piston **162**, **562a-b** in the horizontal direction.

The operation of an extrusion system **100**, **500** of this kind is then as follows. A heated billet is introduced into the container **152**, **552a-b** between the piston **162**, **562a-b** and the extrusion die **154**, **554a-b**. By means of the actuating means **106**, **506** the press **102**, **502** moves the slider **104**, **504** vertically, here downward, and the movement transformation system **180**, **580a-b** transforms the movement of the slider **104**, **504** into movement of the piston **162**, **562a-b** toward the extrusion die **154**, **554a-b**, which pushes the billet **10** through the passage **156**, **556a-b** of the extrusion die **154**, **554a-b** to form the extruded profile **160**, **560a-b**.

An arrangement of this kind enables use of a vertical displacement press that is of high power.

Thus, the slider **104**, **504** is mobile between a first position corresponding to a position of the piston **162**, **562a-b** away from the extrusion die **154**, **554a-b** and a second position corresponding to a position of the piston **162**, **562a-b** close to the extrusion die **154**, **554a-b**.

In the embodiment of the invention shown in FIGS. 1 and 5, the downward vertical movement of the slider **104**, **504** drives the movement of the piston **162**, **562a-b** toward the extrusion die **154**, **554a-b**, but if the press **102**, **502** is disposed lower than the container **152**, **552a-b**, it is upward vertical movement of the slider **104**, **504** that drives the movement of the piston **162**, **562a-b** toward the extrusion die **154**, **554a-b**.

FIGS. 2, 3 and 4 show different variants of the movement transformation system **280**, **380**, **480** in accordance with the first embodiment of the invention. Each movement transformation system **280**, **380**, **480** includes a pinion **282**, **382**, **482**, the rotation axis of which is horizontal and perpendicular to the direction of movement in translation of the piston **162**. The pinion **282**, **382**, **482** is mounted to be mobile in rotation on the chassis **101**. Each movement transformation system **280**, **380**, **480** also includes a first rack **284**, **384**, **484** and a second rack **286**, **386a-b**, **486a-b**.

In the embodiment of the invention presented here, the pinion **282**, **382**, **482** and the first rack **284**, **384**, **484** are common to all the movement transformation systems **280**, **380**, **480** employed in one particular embodiment.

The slider **104** carries the first rack **284**, **384**, **484**, which meshes with the pinion **282**, **382**, **482**. The first rack **284**, **384**, **484** is secured to the slider **104**.

Each piston **162**, and more particularly the associated piston rod **164**, carries the second rack **286**, **386a-b**, **486a-b**

which meshes with the pinion **282**, **382**, **482**. Each second rack **286**, **386a-b**, **486a-b** is secured to the corresponding piston **162**.

Accordingly, vertical movement of the slider **104** drives movement of the first rack **284**, **384**, **484**, which then drives the rotation of the pinion **282**, **382**, **482**, which then drives the movement of the second rack **286**, **386a-b**, **486a-b** and therefore of the piston **162**.

Because of the simultaneous movement of the slider **104**, **10** the piston **162** and the piston rod **164**, and to prevent these elements telescoping when moving, they are offset relative to one another along the rotation axis of the pinion **282**, **382**, **482**.

In each of the embodiments presented in FIGS. 2 to 4 the first rack **284**, **384**, **484** meshes with a lateral part of the pinion **282** and, more particularly, the lateral part facing the press **102**.

In the FIG. 2 embodiment, there is only one piston **162** and therefore only one piston rod **164** and the second rack **286** meshes with a lower part of the pinion **282**, which makes it possible to place the container **152** on the opposite side of the press **102** to the pinion **282**.

In the FIG. 3 embodiment, there are two pistons **162** and therefore two piston rods **164a-b**, and each second rack **386a-b** meshes with a lower part of the pinion **382**, which makes it possible to place the container **152** on the opposite side of the press **102** to the pinion **382**. The movement of the first rack **384** drives the movement of the two second racks **386a-b** in the same direction.

In the FIG. 4 embodiment there are two pistons **162** and therefore two piston rods **164a-b** and one of the second racks **486a** meshes with a lower part of the pinion **482** and the other of the second racks **486b** meshes with an upper part of the pinion **482**, which makes it possible to place a container **152** on each side of the pinion **482**. The movement of the first rack **384** drives the movement of the two second racks **486a-b** in opposite directions.

For reasons of balance, when there are two pistons **162** the two second racks **386a-b**, **486a-b** are disposed on either side of the first rack **384**, **484**.

Moreover, using a rack-and-pinion system enables reduction of losses by friction.

In the second embodiment of the invention (FIG. 5) there are two containers **552a-b** and a movement transformation system **580a-b** for each container **552a-b**, but there could be only one container and therefore only one movement transformation system.

The movement transformation system **580a-b** includes an arm **582a-b** that has a first end that is mounted in articulated manner on the slider **504** and a second end that is mounted in articulated manner on the piston **562a-b** and, more particularly, on the piston rod **564a-b**.

The length of the arm **582a-b** is preferably determined so that when the slider **504** is in its first position, and the piston **562a-b** is in the away position, the arm **582a-b** is at a non-flat angle to the direction of movement of the piston **562a-b** and so that when the slider **504** is in its second position, and the piston **562a-b** is in the close position, the arm **582a-b** is at a flat angle to the direction of movement of the piston **562a-b**, that is to say, the arm **582a-b** and the direction of movement of the piston **562a-b** are aligned.

While at least one exemplary embodiment of the present invention(s) is disclosed herein, it should be understood that modifications, substitutions and alternatives may be apparent to one of ordinary skill in the art and can be made without departing from the scope of this disclosure. This disclosure is intended to cover any adaptations or variations

5

of the exemplary embodiment(s). In addition, in this disclosure, the terms "comprise" or "comprising" do not exclude other elements or steps, the terms "a" or "one" do not exclude a plural number, and the term "or" means either or both. Furthermore, characteristics or steps which have been described may also be used in combination with other characteristics or steps and in any order unless the disclosure or context suggests otherwise. This disclosure hereby incorporates by reference the complete disclosure of any patent or application from which it claims benefit or priority.

The invention claimed is:

1. An extrusion system comprising:
  - a press with a chassis, a slider mounted to be mobile vertically on the chassis, and an actuating means that moves the slider alternately downward and upward,
  - a hollow container for receiving a billet, the hollow container having an extrusion die at one end and a piston mounted at an opposite end, the piston being mobile in translation horizontally in the hollow container, and
  - a movement transformation system arranged between the slider and the piston to transform a vertical movement in translation of the slider into a horizontal movement in translation of the piston.
2. The extrusion system according to claim 1, wherein the movement transformation system comprises:
  - a pinion rotational about an axis of rotation, the axis of rotation perpendicular to a direction of movement in translation of the piston,

6

- a first rack meshed with the pinion and secured to the slider, and
    - a second rack meshed with the pinion and secured to said piston.
5. The extrusion system according to claim 2, wherein the second rack meshes with a part of the pinion below the axis of rotation of the pinion.
4. The extrusion system according to claim 2, further comprising:
  - 10 a second piston, and
  - a third rack meshed with the pinion and secured to the second piston,
  - wherein the third rack meshes with a part of the pinion below the axis of rotation of the pinion.
- 15 5. The extrusion system according to claim 2, further comprising:
  - 10 a second piston, and
  - a third rack meshed with the pinion and secured to the second piston,
  - 20 wherein the second rack meshes with a part of the pinion below the axis of rotation of the pinion, and
  - wherein the third rack meshes with a part of the pinion above the axis of rotation of the pinion.
- 25 6. The extrusion system according to claim 1, wherein the movement transformation system includes an arm having a first end mounted in an articulated manner on the slider and a second end mounted in an articulated manner on the piston.
